Primary Examiner — Bao-Yen T Nguyen*Assistant Examiner* — Emily Anna Saunders(74) Attorney, Agent, or Firm — Gurr & Brande, PLLC; Robert A. Gurr(57) CLAIM

The ornamental design for a golf game target, as shown and described.

DESCRIPTION

The sole FIGURE is a plan view of the golf game target. The broken lines showing a frame around the golf game target are for the purpose of illustrating environmental subject matter and form no part of the claimed design. The golf game target is of conventional thickness that forms no part of the claimed design. The rear side of the golf game target forms no part of the claimed design.

1 Claim, 1 Drawing Sheet(56)
